F. Edson Birt,

UNITED STATES PATENT OFFICE.

EUGENE H. LEWIS, OF ST. JOSEPH, MICHIGAN.

DESIGN FOR A BUILDING-BLOCK.

SPECIFICATION forming part of Design No. 20,287, dated November 11, 1890.

Application filed September 16, 1890. Serial No. 365,178. Term of patent 14 years.

To all whom it may concern:

Be it known that I, EUGENE H. LEWIS, a citizen of the United States, and a resident of St. Joseph, in the county of Berrien and State of Michigan, have invented a certain new and original Design for Building-Blocks, of which the following is a specification, reference being had to the accompanying drawings, forming a part hereof.

10 The leading feature of my design consists of a rectangular margin or border extending continuously around one face of the oblong block or brick, alternate elevations and depressions within said margin or border, with 15 certain of the elevations or raised portions contiguous to the margin or border, and a groove in said raised portions contiguous to the margin or border and parallel with the same.

20 In the drawings, Figure I is an elevation of a rectangular building-block showing my design. Fig. II is a longitudinal sectional view through the block on the line $x-x$ of Fig. I. Fig. III is a transverse sectional view through 25 the block on the line $y-y$ of Fig. I.

A is the rectangular margin or border which extends continuously around the sides and ends of the front oblong face a of the building block or brick. Within this margin or border are irregularly placed the sunken portions, depressions, or cavities B B', which are separated by the raised portions C C' C'', which lie in a plane flush with the margin or border, or substantially so. The series of elevations C' extend in line along the middle of the building-block, while the elevations C C'' are at opposite sides of said middle series, and they lie contiguous to the side edges of the block. The depressions or cavities are 35 irregularly and arbitrarily placed, and the sides b of each depression or cavity lie at

an angle to each other and converge to the bottom b' of such depression. Some of the depressions, as B, are completely isolated from the adjacent cavities, while others of the depressions, as B', are connected to one or more cavities by shallow grooves D, which extend through the face or faces of the elevations or raised portions. In the raised portions contiguous to the margin or border A, I provide 45 the groove E, which extends parallel with the border; but as the raised portions within the border are intersected and divided by the depressions or cavities this groove does not extend continuously around the block and its 50 marginal border, but is only used at certain irregular intervals where the raised portions are contiguous to the marginal border. The irregular cavities or depressions alternating with the raised portions within the border 55 presents to the eye the combined effect of a smooth marginal border and elevations on the plane of or flush with said border, and which are divided or intersected by the irregular 60 cavities or depressions placed arbitrarily in 65 the face of the block, all being within and inclosed by the margin or border.

Having thus described my invention, what I claim is—

The design for a building-block herein 70 shown and described, the same comprising the raised marginal border, the irregular cavities or depressions within said border, and the raised portions alternating with said cavities and lying flush with the raised border, as 75 set forth.

In testimony whereof I affix my signature in presence of two witnesses.

EUGENE H. LEWIS.
